DESIGN FOR A COMBINED HANDBAG, WALLET, AND CIGARETTE CASE

Benjamin H. Bryon, New York, N. Y.

Application January 6, 1936, Serial No. 60,445

Term of patent 3½ years

To all whom it may concern:

Be it known that I, Benjamin H. Bryon, a citizen of the United States, residing at New York city, in the county of New York and State of New York, have invented a new, original, and ornamental Design for a Combined Handbag, Wallet, and Cigarette Case, of which the following is a specification, reference being had to the accompanying drawing, forming a part thereof.

Fig. 1 is a perspective view of a combined handbag, wallet and cigarette case, in closed position, showing my new design.

Fig. 2 is a similar view, showing the same in open position.

Fig. 3 is a back perspective view of Fig. 2.

I claim:

The ornamental design for a combined handbag, wallet and cigarette case, as shown.

In testimony whereof I have affixed my signature.

BENJAMIN H. BRYON.
